UNITED STATES PATENT OFFICE.

GEORGE R. JOUGHINS, OF ELIZABETH, NEW JERSEY.

RAILWAY BOX FREIGHT CAR.

Application filed September 14, 1927. Serial No. 219,490.

My invention embraces the construction of steel railway box car bodies having self supporting sides, of pressed forms of corrugated steel plates which entirely eliminates the usual side sills and the usual side framework consisting of steel struts and braces and the use of lumber or other siding, with the object of simplifying the construction of said cars and of materially reducing the number 10 of parts and the amount of labor involved in their manufacture.

In the accompanying drawing, Figure 1 is an outside side elevation of the car. Figure 2, on a larger scale, a half section transverse 15 elevation at A—A, and a half section through the side at B—B. Fig. 3 is a small portion of the side sheets at C—C.

Fig. 4 is an elevation, Fig. 5 a plan, Fig. 6 a section on line D—D Fig. 4, and Fig. 7 an 20 end view of the key of the arch.

The side sheets are designed to be of sheet 25 steel, heavy enough to be self supporting, including the proportion of the load usually sustained by the side sills.

In the drawing the sheets are shown having an arch formation springing from the body bolsters 1; the shank 2 of the arch being formed of corrugations in the sheet steel. The lower parts of the car sides, 3, form 30 the chord of the arch and may be flanged inwardly, to increase its tensile area, as shown at 4, and it may be further strengthened under the doorway by reinforcements, 15, rigidly attached to the steel plate. The shank of the arch may be curved as at, 5, or straight as at 6. The key of the arch is shown at 7, over the doorway. Its lateral ends are flattened and spread out, 8, and rigidly secured to the shanks. Short corrugations are shown 35 in the face of the key, as at 9, to fit corresponding corrugations in the sheets as shown. The remaining part of the sheets above the doorway being preferably left plain. Rivets, 40 10, are used to rigidly connect the key to the

sheets, and, as the key is also a joint plate, it 45 connects the sheets to each other.

The filling in, or remaining parts of the sides are preferably of corrugated steel sheets, 50 preferably integral with the arch so far as possible, to give sidewise stiffness and also to provide flexibility for expansion and contraction where needed.

The side sheets are shown turned inwardly at 4 and may be further turned upwards at 55 9 to support the flooring.

A strut to support the end of the car body from the body bolster is shown at 10, it is also 60 preferably of corrugated form pressed in the plate.

11 are the center sills, 12 the intermediate 65 sills, 13 the carlines and 14, the flooring, preferably of metal.

What I claim is:

1. A railway box freight car having its 65 sides constructed of self supporting metal sheets which form a continuous girder from end to end, situated upon the body bolsters and having portions of said side sheets pressed into corrugations integrally forming the shanks of an arch springing from said 70 bolsters and meeting above the doorways to form a key, and with a lower chord to complete a self sustaining arch, substantially as described.

2. A railway box freight car having its 75 sides constructed of self supporting metal sheets which form a continuous girder from end to end, situated upon the body bolsters and having portions of said side sheets pressed into corrugations integrally forming 80 the shanks of an arch springing from said bolsters and meeting above the doorways to form a key, and the lower edge of said side sheets left plain and uncorrugated to form a lower chord or tie rod integral with said side 85 sheets substantially as described.

GEORGE R. JOUGHINS.
